GERRET REKERS, OF ROCHESTER, NEW YORK, ASSIGNOR TO GENERAL RAILWAY SIGNAL COMPANY, OF GATES, NEW YORK, A CORPORATION OF NEW YORK.

SEMAPHORE-SIGNAL MECHANISM.

1,272,099.

Specification of Letters Patent.

Patented July 9, 1918.

Application filed April 21, 1913. Serial No. 762,570.

To all whom it may concern:

Be it known that I, GERRET REKERS, a citizen of the United States, and a resident of the city of Rochester, in the county of Monroe and State of New York, have invented a new and useful Semaphore-Signal Mechanism, of which the following is a specification.

This invention relates to that class of devices which are employed in railway signaling and which are ordinarily termed, semaphore operating mechanisms.

The primary object of this invention is to design and construct a mechanism for operating a semaphore, such that the semaphore will be moved from a biased to an operated position by the operation of any well known form of rotary motor through the intermediary of reduction gearing, but in which the semaphore may be allowed to fall to its bias position without being obliged to rotate the reduction gearing.

Other objects and advantages will become apparent to those skilled in the art as the description of the invention progresses, and the novel features of the invention will be particularly pointed out in the appended claims.

In describing the invention in detail, reference is had to the accompanying drawings, wherein I have illustrated a preferred physical embodiment of my invention, and wherein like characters of reference designate corresponding parts throughout the several views, and in which:

Figure 1, is a view in sectional elevation of the semaphore operating mechanism constructed in accordance with my invention taken on the line A—B of Fig. 5, viewed in the direction of the arrow W, which also shows a fragment of a semaphore in side elevation and a circuit controller in elevation with certain parts broken away; Fig. 2, is a sectional elevation on the line E—F of Fig. 1, viewed in the direction of the arrow K; Fig. 3, is a sectional elevation on the line E—F of Fig. 1 viewed in the direction of the arrow J; Fig. 4, is a rear elevational view of the case containing the semaphore operating mechanism showing the circuit controller attached thereto and a fragment of a semaphore in the biased position; Fig. 5, is a sectional elevation on the line C—D of Fig. 1, viewed in the direction of the arrow M; Fig. 6, is an enlarged detail sec-

tional elevation of a clutch member on the line E—F viewed in the direction of the arrow J; Fig. 7, is an enlarged detail elevation of a clutch member and gear used in my invention; Fig. 8, is a detail view of a latch member; Fig. 9, is an elevational view of the right hand side of the latch member shown in Fig. 8; Fig. 10, is a schematic view illustrating a conventional semaphore and the operating mechanism and circuit controlling the same; Fig. 11, is a view partly in section on the line G—H, Fig. 4, viewed in the direction of the arrow, showing the method of securing the latch member in the rear cover of the mechanism case.

1, designates a casing formed with an opening at its rear end which may be closed by the cover 2, which is attached to the casing 1 by means of screws 3, best shown in Fig. 4.

The casing 1, contains two continuous lugs 4 and 5, best shown in Fig. 1, on its inside surface. The lugs 4 and 5 support and hold firmly in place a magnetic stator member 6, which is provided with any usual and well known type of stator winding 7. Within the stator is positioned a rotor 8, formed of magnetic material 9 which is provided with the usual and well known rotor winding 10, which is connected in the usual and well known manner to the segments of the commutator 11. The type of motor illustrated in this particular physical embodiment, is considered to be a series wound motor, which is connected in the usual manner and to which connection is made by means of brushes 12 bearing upon the commutator 11, as shown in Fig. 3. The rotor 8 is firmly attached to the hollow shaft 13, which is journaled so as to rotate freely about the sleeves 14 and 15 placed on the shaft 16. The shaft 16 is journaled in the anti-friction bearings 17 and 18 which are supported by the case 1 and the cover 2 respectively.

In the rear of the case a holding stator 19 is positioned, which is formed of magnetic material and has poles 20, each of which has a coil of insulated wire 21 placed thereon. The coils are connected in a series circuit, the terminals of which are wires 22 and 23 as shown in Fig. 2. Within the holding stator 19 is positioned a holding rotor 24, which is journaled so as to be free to move on the sleeve 25 and which has 110

polar-projections 30 corresponding with the poles 20 of the holding stator. A bearing 26 is formed in the holding rotor, and in this bearing a shaft 27 is journaled. This shaft 27 is formed into a gear 28 at one end, and has keyed thereto at the other end, the gear wheel 29.

The sleeve 13 has a gear 31 formed on one of its ends, best shown in Fig. 2, which 10 meshes with gear 29 on shaft 27, also well shown in Fig. 2. Sleeve 13 has also a clutch member 32, best shown in Fig. 6, formed thereon. This clutch member has a plurality of cut-away portions on its periphery, 15 so formed, that one end of the cut-away portion is of less depth than the other end, and in each cut-away portion is positioned a ball 33, which is spring pressed by a spring 34 toward the shallow end of the cut-away portion. Positioned about the clutch member is an outer clutch member 35, which has a groove 36 formed therein, in which the balls 33 rest, and which has notches 37 formed in its outer periphery. The notches 20 37, in the outer clutch member 35, each receive an arm 38, shown in Fig. 1, and also in Fig. 2, which arms are rigidly attached to the holding rotor 24, so that outer clutch member 35 must move in unison with holding rotor 24.

A clutch member 39, similar in all respects to clutch member 32, and best shown by Fig. 7, is keyed to shaft 16. The clutch member 39 has associated with it an outer 35 clutch member 40, which has a groove 41 similar to the groove 36, of outer clutch member 35, but the outer clutch member 40 has its periphery formed into teeth which engage with the teeth of gear 28, formed on shaft 27, best shown in Fig. 5.

The hold clear rotor 24, as best shown in Fig. 5, has its rear face formed into a series of latching notches 42, which are adapted to engage with latch 61 to prevent a rotation 45 of the holding rotor 24 in the direction of the arrow *u*, Fig. 5. The latch 61 shown in detail in Figs. 8, 9, and 11 is formed with a hole 43, by which the latch is journaled on a pin 44, best shown in Figs. 4 and 11. The 50 latch is provided with a piece of rubber or similar material 45, which passes through the latch and rests against the holding rotor 24, and which reduces the noise caused by the movement of latch 61 caused by a rotation 55 of the holding rotor 24, in a direction opposite to the arrow *u*.

The cover 2 of the case 1 has a circuit controller bolted thereto by means of bolts 46 best shown in Fig. 4. This circuit controller 60 comprises a supporting plate 47 which has projecting arms 48 and 49, connected at their outer end by means of web 50 and at their inner end by means of plate 47, and support blocks 51 of insulating material. The blocks of insulating material

51 support adjustable contact fingers 52 by means of binding posts 53. The shaft 16 is extended through the rear face of the cover 2, so as to have its outer end journaled in the member 50. Between plate 47 and member 70 50, is situated a drum of insulating material 54, rigidly attached to the shaft 16 by means of screw 55. The drum of insulating material 54 carries metallic strip 106 which is positioned so as to lie in the path of contact 75 fingers 52. This circuit controlling device is substantially identical with that shown, described and claimed in the patent numbered 1,224,542, granted to William S. Henry May 1st, 1917. The circuit controller has, however, one feature not shown in the above mentioned patent, which is known as a slip contact, and consists of a spring arm 56 attached to insulating block 51, in the same manner as contact fingers 52 are attached 80 and bears at its outer end a cup-shaped member 57, in which one end of a pin 58 is loosely positioned. The other end of the pin 58 is loosely positioned in a cavity formed in a member 59. The member 59 90 is formed with an arc shaped face which bears against the insulating drum 54. The rotation of drum 54 in the direction of the arrow *P*, Fig. 4, causes an upward movement of member 59, but a movement of insulating drum 54 in a direction opposite to arrow *P* causes the member 59 to move downwardly and into contact with a contact finger as 52, positioned in line with it and supported by a lower insulating block 100 51 as best shown in Fig. 4.

When current is applied to the electric motor, the rotor of which has been designated 8, a clock-wise rotation viewing the rotor from the left in Fig. 1 or rotation in the direction of the arrow *S*, Fig. 1, will take place thereby causing a similar rotation of shaft 13, which will cause gear 31 to rotate. The rotation of gear 31 causes gear 29 to rotate in a counter clock-wise direction and as gear 28 is rigidly attached to gear 29 by means of shaft 27 a counter-clockwise rotation of gear 28 will take place, and as gear 28 meshes with outer clutch member 40 a clock-wise rotation of outer clutch member 40 will take place thereby causing the balls of the inner clutch member to move toward the shallow end of the cut-away portion of the inner clutch member 39, so binding the inner and outer clutch members firmly together, and as inner clutch member 39 is keyed to shaft 16 a clock-wise rotation of shaft 16 will take place which will cause semaphore 60 attached thereto to be moved to an operated position.

During the operation just described the inner clutch member 32 and the outer clutch member 35 will not be caused to rotate in unison because inner clutch member 32 will rotate in the direction of the arrow *T*, Fig. 130

6, and so balls 33 will move to the deepest part of the cut-away portions in which they rest, thus preventing any binding between inner clutch member 32 and outer clutch member 35.

As gears 28 and 29 are somewhat in the nature of a floating gear supported by rotor 24, there will be a tendency to move rotor 24 in the direction of the arrow U, Fig. 5, but such tendency will be resisted by latch 61 and holding rotor 24 will be held in the position shown in Fig. 5, so that, the polar-projections 30 of the rotor 24 will not coincide with the poles 20 of the holding stator.

When the semaphore 60 has been moved to the full clear position the current to the electric motor will be interrupted and just before the semaphore reaches the full clear position, current will be fed to terminals 22 and 23 of the coils of the holding stator, so that the holding stator 19 can, by reacting on the holding rotor 24, hold the semaphore in the moved position. The holding action takes place through the shaft 16 keyed to the inner clutch 39, which by reason of the bias of the semaphore tends to move in a counter clock-wise direction and so tends to move the outer clutch member 40, which being in mesh with gear 28 tends to turn shaft 27 and gear 29 in a clock-wise direction, but a turning movement of gear 29 in a clock-wise direction tends to move gear 31 in a counter clock-wise direction and as gear 31 is rigidly attached to sleeve 13, upon which inner clutch member 32 is formed, there is a tendency to move inner clutch member 32 in a counter clock-wise direction, that is in a direction opposite to the arrow T of Fig. 6, so that inner clutch member 32 moves so that balls 33 are positioned in the shallow end of the cut away portion of the inner clutch member thus transmitting a tendency to move in a counter clock-wise direction to outer member 35. The outer clutch member 35 being rigidly attached to holding rotor 24 by means of arms 38 tends to move holding rotor 24 in a counter clock-wise direction, that is, in a direction opposite to the arrow U Fig. 5, but the magnetic attraction of the poles 20 of the holding stator 19, upon the polar projections 30 of the holding rotor 24, prevents any movement of holding rotor 24.

When the flow of current through the coils of holding stator 19 is interrupted, the holding rotor 24 is free to move so that the force exerted by the semaphore 60 causes a counter clock-wise rotation of shaft 16, clutch member 39 and outer clutch member 40, thereby causing a clock-wise rotation of gear 28, shaft 27 and gear 29, which causes a counter clock-wise rotation of gear 31, sleeve 13, and inner clutch member 32, which causes outer clutch member 35 to be bound tightly to inner clutch member 32 which

transmits its motion through arms 38 to holding rotor 24, causing holding rotor 24 to rotate in a counter clock-wise direction, and at the same time causes rotor 8 to also move in a counter clock-wise direction as 70 rotor 8 is firmly attached to sleeve 13.

The movement of semaphore 60 to the biased position will therefore take place with either no movement at all of the reduction gearing, through which it was 75 moved to the clear position, or at most, through a movement just sufficient to bind inner clutch member 32 and outer clutch member 35 together. Even the slight movement mentioned is, however, not necessary, 80 because if anything prevents a slight movement between gear 29 and gear 31, the parts will act just as though the slight movement had taken place, as the slight movement which may normally take place is merely 85 that which is necessary to bind inner clutch member 32 and outer clutch member 35 together, but if these two parts move together without any previous binding by means of balls 33 then of course the slight motion is 90 unnecessary.

It must now be seen that applicant has designed a semaphore operating mechanism by means of which a semaphore is moved from the biased position to an operated position through the intermediary of reduction gearing which revolves upon its own axis during a movement of the semaphore to an operated position but which moves as a whole when the semaphore moves to 100 the biased position from an operated position, so that, the force which the semaphore is capable of exerting by reason of its bias is capable of exerting its greatest possible effect to cause the rotor of the operating 105 motor to rotate backwardly.

In Fig. 10, I have shown schematically the operating mechanism case and designated it by 1, the semaphore as 60, the insulating blocks 51, the drum 54, and the 110 contact fingers and metallic strips to connect therewith. 62 designates a source of current; 63, a switch arm which may be moved from the position shown to the dotted line position; 64, another switch arm 115 which may be moved from the full line position to the dotted line position.

With all of the parts as shown in Fig. 10, current will flow as follows: positive terminal of battery 62, wire 65, switch arm 120 63, wires 66 and 67, switch arm 64, wires 68 and 69 to contact finger 70, metallic strip 71, contact finger 72, wires 73 and 74 to terminal 22 shown in Fig. 2, and then from terminal 23 shown in Fig. 2 to wire 75, and 125 to the negative terminal of the battery 62. Current flowing in the above traced path will cause the poles 20 to magnetically attract the polar projections 30 on the rotor 24 and so hold the rotor 24 from movement, 130

- If switch arm 64 is moved to the dotted line position the flow of current through the whole holding stator coil will be interrupted and the drum 54, by reason of the bias of 5 semaphore 60, will be rotated backwardly. The backward rotation of drum 54 will cause member 59 to contact with contact finger 76, so that when the drum has been rotated backwardly sufficiently for strip 77 10 to make contact between contact fingers 78 and 79 a circuit will be formed in which current flows as follows: positive terminal of battery 62, wire 65, arm 63, wires 66 and 80, contact finger 78, strip 77, contact finger 15 79, wires 81 and 82, contact finger 83, member 59, contact finger 76, wires 84 and 85 to one of the brushes 12, as shown in Fig. 3, and through the armature and field coils leaving by one end of the winding of the 20 field coil, to wire 75 and to the negative terminal of the battery 62. Current in the above traced path would cause such an energization of the operating motor that it would tend to move the semaphore 60 toward an operated position, but, the action 25 is merely momentary, for the strip 77 is so adjusted in its position on the drum 54, that it makes contact between strip 78 and 79 just before the semaphore 60 reaches the 30 caution position and breaks contact with strip 79 immediately thereafter, so that the effect is merely that of a dash pot to bring the semaphore 60 to rest at the caution position.
35. When the semaphore 60 reaches the caution position a circuit is formed in which current flows as follows: positive terminal of the battery 62, wire 65, arm 63, wires 66, 86 and 92, contact finger 93, metallic strip 40 94, caused to bridge fingers 93 and 95 by the backward movement of the drum 54 caused by the fall of the semaphore 60, contact finger 95, wires 96 and 74 to terminal 22 as shown in Fig. 2, and from terminal 23 45 shown in Fig. 2, to wire 75, and thence to the negative terminal of the battery. Current flowing in the above traced path will prevent a movement of holding rotor 24 so that the semaphore arm 60 will be held in 50 the caution position.
- If switch arm 63 is moved to the dotted line position the circuit through which current flows to hold the semaphore 60 in the caution position will be broken and, consequently the arm by reason of its bias will move to the danger position and in so doing will again rotate drum 54 backwardly causing member 59 to contact with contact finger 76, if it is not already in contact therewith, thus forming an electrical dash pot circuit in which current flows as follows: positive terminal of the battery 62, wire 65, switch arm 63 in the dotted line position, wire 97, contact finger 98, metallic strip 99, 60 contact finger 100, wire 82, spring 83, mem- 65 ber 59, contact finger 76, wires 84 and 85, one of the brushes 12 of the operating motor, through the armature and field coils leaving by one end of the winding of the field coil of the operating motor and wire 75 to the negative terminal of the battery 62. The metallic strip 99 would only make momentary connection between contact fingers 98 and 100, and when the semaphore has arrived at its full bias position will have 75 broken contact between the two fingers 98 and 100 so that the effect will be merely that of a dash-pot acting temporarily to restrain a too violent motion of the semaphore 60 to the bias position.
- The return of the semaphore 60 to the bias position will cause metallic strip 89 to bridge contact fingers 88 and 90 so that if the switch arm 63 were again moved to the full line position current would flow in the following path: positive terminal of battery 62, wire 65, arm 63, wires 66, 86 and 87, contact finger 88, metallic strip 89, contact finger 90, wires 91 and 85 to one of the brushes 12 of the operating motor through the armature and field coils leaving by one end of the winding of the field coil of the operating motor to the wire 75 and thence to the negative terminal of the battery 62. Current flowing in the above traced path would cause the rotor of the operating motor to rotate in a clock-wise direction and move the semaphore arm to the caution position at which point metallic strip 89 will have moved from in contact with contact finger 88, thus breaking the operating circuit, but at the same time contact 94 will have moved so as to bridge contact fingers 93 and 95 so that the holding circuit for the caution position of the semaphore heretofore traced will be formed.
- If after the semaphore 60 has arrived at the caution position, the switch arm 64 is moved to the full line position and switch arm 63 is still in the full line position, then as metallic strip 101 moved so as to bridge contact fingers 102 and 103 by the movement of the semaphore to the caution position, current will flow in a path as follows: positive terminal of the battery 62, wire 65, 110 arm 63, wires 66 and 67, arm 64, wires 68 and 104, contact finger 102, metallic strip 101, contact finger 103, wires 105 and 85 to one of the brushes 12 of the operating motor, through the armature and field coils 115 leaving by one end of the winding of the field coil of the operating motor to wire 75 and thus to the negative terminal of the battery 62. Current flowing in the above traced path would cause the semaphore 60 to be moved to the full clear operated position and the drum 54 moved so that metallic strip 71 makes contact between contact finger 70 and contact finger 72, so that the holding circuit for the full clear operated 120 125 130

position of the semaphore heretofore traced would be formed.

In those types of semaphore operating mechanism heretofore employed in which the armature of the operating motor revolves backwardly when the semaphore falls to the full biased position it has been customary to restrain a too violent motion of the semaphore to the danger position by short circuiting the terminals of the operating motor just before the semaphore reached either the caution or full biased position. Such a method is, however, inapplicable to the semaphore mechanism constructed in accordance with applicant's invention because the total arc of movement of the rotor of the operating motor is only that through which the semaphore itself moves, so that with a semaphore moved through an arc of 90°, the total arc of movement of the rotor of the motor would only be 90°, which would not be sufficient to generate sufficient current to effectually damp the movement of the semaphore in its downward movement if the terminals of the operating motor were shunted just before the semaphore reached either the caution position or the full biased position, therefore applicant has devised the means herein shown which includes the slip contact.

The arrangement and construction of parts, including the slip contact, for temporarily supplying current to the operating motor when the semaphore moves toward its biased or stop position, for the purpose of snubbing or retarding the movement of the semaphore, is applicable to types of semaphore operating mechanisms other than the particular type shown and described, particularly to those types in which an alternating current motor is used; and in my co-pending application Serial No. 110,313, filed July 20, 1916, I have disclosed and claimed my invention including the slip contact applied to another type of semaphore operating mechanism illustrative of the general application of my invention.

Applicant's invention is thus seen to provide a semaphore operating mechanism which by reason of the use of reduction gearing, will allow the use of a low powered motor. In fact the gear reduction between the operating motor and the semaphore, can be made so great, that the amount of force needed to be exerted at gear 31 to prevent a backward rotation of the gear 31 on its axis, due to the bias of the semaphore 60 would be extremely slight so that the slightest impediment offered to the rotation of gear 31, would prevent a movement of the semaphore 60 to the biased position. Such a large gear reduction would, of course, result in a considerable saving in electrical energy needed to cause the operating motor to move and is therefore very de-

sirable and as applicant's invention provides a means for allowing the semaphore to move to its bias position without a rotation of the reduction gearing upon its axis, but as a whole, no fear need be entertained that the mechanism by which a decided economy of electrical energy is obtained will result in an apparatus in which there is a possibility that the semaphore will not return to its bias position when released, due to a slight impediment offered to the rotation of the reduction gearing employed therein.

It is evident that various modifications may be made in the detail construction of the operating gearing connecting the motor and the semaphore; and in my co-pending application Serial No. 110,312, filed July 20, 1916, I have shown another form of my invention and claimed broadly a construction and arrangement of parts whereby the semaphore will be operated by the motor through reduction gearing, but will be directly connected to the motor when returning from an operated position toward its biased position.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In an electric signal mechanism, in combination: an oscillatable member having a biased and a set position; a motor for causing the member to assume the set position; a shaft connected to the motor; a shaft connected to the member; a train of gear wheels having one end wheel connected to the shaft of the motor; a clutch for connecting the other end wheel and the shaft of the member when said member is assuming set position; a rotatable device of magnetic material mounted for turning in the direction of rotation of said member when assuming the biased position; a clutch for connecting the shaft of the member and the device when the member is assuming the biased position; the intermediate gear wheels in said train being operably mounted on the said device and movable therewith, and means for magnetically holding the rotatable device from turning.

2. In an electric signal mechanism, in combination: a shaft, an oscillatable member connected to the shaft and having a biased and a set position; a rotatable device formed of magnetic material; a fixed object; a latch connected to the fixed object and the rotatable device for preventing the device from turning in the direction of the member when assuming set position; a clutch for connect-

ing the shaft and the device when said member is assuming the biased position, and means for magnetically holding the rotatable device from turning.

5 3. In an electric signal mechanism, in combination: an oscillatable member having a biased and a set position; a motor for causing the member to assume its set position; a rotatable device formed of magnetic material; means for preventing the device from turning in the direction of rotation of the member when assuming set position; means for connecting the said member, the motor and the device for synchronous movement 10 when the said member is assuming the biased position and means for magnetically holding the rotatable device from turning.

4. In a signal operating mechanism, in combination: an oscillatable arm having an operated position and a biased position; an electric motor for operating said arm; an operating connection between said motor and said arm including a reduction gearing; means interposed in said connection and automatically operated by the movement of said arm to its biased position for interrupting said connection; means operated automatically by the movement of said arm to its biased position for operatively connecting said motor and said arm; an operating circuit for said motor; and circuit controlling means included in said motor operating circuit and governed by the movement of said arm, said circuit controlling means temporarily closing said motor operating circuit near the biased position of said arm when said arm moves toward its biased position.

5. In a semaphore signal operating mechanism, in combination: a semaphore; a motor for operating said semaphore to either of two operated positions; means including reduction gearing for operatively connecting said motor to said semaphore upon energization of the motor to move the semaphore to an operated position, said means acting when the semaphore moves toward its biased position to render the reduction gearing ineffective and to establish a direct connection between the motor and the semaphore; and means for retarding the return movement of said semaphore to its biased position.

6. In an electric signal mechanism, in combination: a semaphore having an operated position and a biased position; a motor for operating said semaphore; a holding rotor of magnetic material; a fixed stator arranged in coöperative relation with said rotor and having an energizing winding; reduction gearing carried by said rotor and operatively connecting said semaphore and said motor; means for permitting rotation of said rotor relative to said motor in one direction and preventing said rotation in the opposite direction; a source of current; and 65 circuit controlling means for controlling the

connection from said source of current to said motor and to the winding of said stator.

7. In an electric signal mechanism, in combination: a semaphore having an operated position and a biased position; a shaft connected to said semaphore; a motor for operating said semaphore; a shaft connected to said motor; a holding rotor of magnetic material; a train of gears having one end gear connected to the shaft of the motor and its other end gear connected to the shaft of the semaphore, the intermediate gears in the said train being carried by said rotor and being movable therewith; means connecting said rotor and the shaft of the motor and permitting relative movement thereof in one direction only; and a fixed stator arranged in coöperative relation with said rotor and adapted when energized to prevent rotation of said rotor.

8. In an electric signal mechanism, in combination: a semaphore having an operated position and a biased position; a shaft connected to said semaphore; a motor for operating said semaphore; a shaft connected to said motor, the shaft of the semaphore and the shaft of the motor being arranged concentrically; a holding rotor of magnetic material; a train of gears having one end gear connected to the shaft of the motor and the other end gear connected to the shaft of the semaphore; the intermediate gears of said train being carried by said rotor and being movable therewith; means connecting the shaft of the motor and said rotor and permitting rotation of said motor shaft relative to said rotor when the motor shaft is rotated in the direction to move the semaphore to its operated position but preventing such relative rotation in the opposite direction; a fixed stator arranged in coöperative relation with said rotor and adapted when energized to prevent rotation of said rotor; a source of current; and circuit controlling means for governing the connection between the source of current and said stator and said motor.

9. In an electric signal mechanism, in combination: a semaphore having an operated position and a biased position; a motor for operating said semaphore; means including reduction gearing for operatively connecting said semaphore and said motor upon energization of said motor to move the semaphore to its operated position; means for directly connecting the semaphore and the motor upon movement of the semaphore to its biased position; and means for energizing the motor to retard the semaphore during a portion of its return movement to its biased position.

10. In a semaphore signal operating mechanism, in combination: a semaphore having an operated position and a biased position; a motor for operating said sema-

phore; a train of gears adapted to connect said motor and said semaphore; means for operatively connecting said semaphore to said motor through the intermediary of 5 said train of gears when said motor drives the semaphore to its operated position and for allowing the train of gears to be moved as a whole upon movement of the semaphore to its biased position; and means for 10 energizing the motor to retard the semaphore during a portion of its return movement to its biased position.

11. In a semaphore signal operating mechanism, in combination: a semaphore 15 having an operated position and a biased position; a motor for operating the semaphore; a rotatable member; reduction gearing carried by said member and operatively connecting the motor and the semaphore; 20 means for directly connecting said member and said motor when the semaphore moves from its operated position to its biased position; means for magnetically holding said member against rotation; and means 25 for energizing the motor to retard the sem-

aphore during a portion of its return movement to its biased position.

12. In a semaphore signal operating mechanism, in combination: a semaphore having an operated position and a biased 30 position; a motor for operating said semaphore; means including reduction gearing and rendered effective only when the semaphore is moved toward its operated position for operatively connecting the semaphore 35 and the motor; means rendered effective only when the semaphore moves toward its biased position for directly connecting the motor and the semaphore; a circuit controller governed by the semaphore and 40 closed only when the semaphore moves toward its biased position; an operating circuit for the motor including said circuit controller; and means for closing said operating circuit for part of the movement of the 45 semaphore near its biased position.
